UNITED STATES PATENT OFFICE.

SILAS C. SCHOFIELD, OF FREEPORT, ILLINOIS.

GRINDING-MILL.

SPECIFICATION forming part of Letters Patent No. 310,916, dated January 20, 1885.

Application filed January 14, 1884. (No model.)

To all whom it may concern:

Be it known that I, SILAS C. SCHOFIELD, a resident of Freeport, in the county of Stephenson and State of Illinois, have invented certain new and useful Improvements in Grinding-Mills; and I do hereby declare the following to be a full, clear, and exact description of the invention, such as will enable others skilled in the art to which it pertains to make and use the same.

My invention is an improved sweep-actuated grinding-mill adapted for grinding small or shelled grain. Its construction is fully described and explained in the following specification and shown in the accompanying drawings, in which—

Figure 1 is a plan of the mill, mounted on a suitable meal-box; Fig. 2, an elevation (looking in the direction indicated by the arrow α , Fig. 1) of the central portion of the cross-bar O and lug Q, which engages with it, the lug being cut by a vertical plane passing through the line $x' y'$, Fig. 3; Fig. 3, a central vertical section of the mill through the line $x y$, Fig. 1, the meal-box being shown in elevation and partly broken away to show the mill; Fig. 4, a vertical cross-section (enlarged scale) showing the joint between the bed-plate T and rotating ring S; Fig. 5, a bottom plan showing the connection of the bed-plate T and the outer grinding-ring, L'; and Fig. 6, an enlarged vertical section of the base-plate T, grinding-ring L', and the means by which they are connected.

In these views A is a preferably rectangular meal-box, having its ends gained into its sides, as shown, and its side pieces connected at the ends by cross-rods D D, each of which is provided at one end with an eye, d, and at the other end with a nut, d', by means of which the side pieces may be drawn together. The eyes d d are at diagonally-opposite corners of the box, and through them pass anchoring loops or rods C C, which are attached at their outer ends to anchoring-stakes N N. The movable portion of the mill rotates in the direction indicated by the arrow α' , Fig. 1, and the resistance to torsional strain, which is ordinarily borne by the meal-box, is transferred to the cross-rods D, anchoring-rods C, and stakes N. The most advantageous position for the rods C is evidently in lines tangent to a circle concentric with the mill, and I do

not therefore limit their application to the particular position in which they are shown. On the meal-box rests an annular base-plate, 55 T, Fig. 3, provided with three integrally-formed ears, E, by means of which it is fastened to the box. The upper edge of the annular base-plate is provided with a groove, e, on both margins of which are beveled surfaces b b, inclined downward and away from the edges of the groove. (See Figs. 3, 4.)

Within the base T is a grinding-ring, L', provided with grinding-teeth on its inner face, and fastened to the base by means of a 65 series of ears, c, extending outward from the lower edge of the grinding-ring, and a series of bolts, passing upward through said ears and through the base-plate T. By inserting washers of any desired thickness between the 70 bottom of the base-plate T and the ears c the ring L' may be placed at any desired height with reference to the base-plate, and, if necessary, washers of different thickness may be placed on the different ears, for the purpose 75 of throwing the grinding-ring into or out of level.

On the annular base-plate T rests a ring, S, whose lower edge rests on and conforms to the upper edge of the base-plate, the central portion of said lower edge being convex and resting in the groove e, hereinbefore referred to, while on the opposite sides of such convex portion are two downwardly-inclined lips, a a', which coincide with the inclined faces b b 85 of the annular base-plate. (See Fig. 4.) The result of this construction is the complete exclusion of dirt, meal, or any other foreign substance from the impinging surfaces of the ring S and base-plate T, and the consequent decrease of friction of those surfaces. The ring 90 S is provided with a series of integrally-formed converging arms rising from the ring to their point of intersection at the center of the mill, and through their intersection passes a vertical bolt, R, having at its lower end a head 95 which supports a cone, G. The upper end of the bolt is screw-threaded, and provided with a nut, I, by means of which the cone may be raised or lowered. The nut I is turned by 100 means of a wrench, J, consisting of a handle or lever and a socket to receive the nut. The socket has vertical sides which conform to the shape of the nut, and an integrally-formed

bottom which lies under the nut, and has a central opening through which the bolt passes. The wrench is thus held in place on the nut so long as the latter remains on the bolt, and 5 is much more convenient than an ordinary detachable wrench.

To the outer edge of the cone G is rigidly attached a grinding-ring, L, provided with suitable grinding-teeth on its outer face, and 10 adapted to co-operate with the grinding-ring L already described. The suspension of the cone by a single bolt passing through its vertex allows it sufficient oscillatory motion for necessary adjustment to the grinding-ring 15 L, and prevents unequal grinding at different points in its periphery. On the upper surface of the cone, near its outer margin, are a series of lugs, K, Figs. 1 and 3, corresponding in number and arrangement to the arms 20 H of the ring S, and on the lower side of each of the arms H, just inside of the ring S, is a downwardly-projecting lug, M, which is adapted to engage with one of the lugs K of the cone, so that rotation of the ring S and its arms H 25 necessarily produces simultaneous rotation of the cone without affecting the oscillatory motion of the cone, which has been already referred to. The ring S is provided with two diametrically-opposite integrally-formed trunnions, V V, on which are pivoted two converging levers, B B, Fig. 1, connected at their point of intersection, and held together by a cross-bar, O, Figs. 1 and 3. At the center of the cross-bar is a gain or recess made by cutting 30 away the lower half of that face of the cross-bar next the mill, the recess being of sufficient length and breadth to receive a lug, Q, formed integrally with the ring S, and of sufficient height to allow considerable vertical movement 35 of the cross-bar without striking the lug. A stirrup, P, crosses the recess in the plane of the lower face of the cross-bar, its legs passing up through the cross-bar and being secured by nuts. The stirrup P and the portion 40 of the cross-bar above the recess form the limits of motion of the sweep. Within these limits it moves freely up or down to accommodate itself to the inequalities of the ground or the varying motion of the horses, but movement above the prescribed limit is prevented 45 by the stirrup, while movement below this is stopped by the striking of the cross-bar on the upper surface of the lug Q.

I am aware that it is not new to suspend a 50 grinding-cone from a movable ring resting on the base-plate, the ring and cone being provided with such means of connection as to insure their simultaneous rotation. So far as I know, however, the connection between the 55 ring and cone has been at the center instead

of at the periphery, as shown and described in this patent. Since the sweeps are attached to the periphery of the moving ring, it is evident that when the connection of the ring and cone is at the center, the converging arms of 65 the ring must be strong enough to transmit the power from the periphery to the center of the mill. Where the connection is at the periphery, however, as shown in this application, the arms which support the cone have no 70 torsional strain to withstand, and need only such strength as is sufficient to support the weight of the mill.

Having now described my invention, what I claim as new, and desire to secure by Letters 75 Patent, is—

1. The combination of a sweep-actuated grinding-mill, a meal-box supporting said mill, cross-rods binding together the opposite sides of said meal-box, and each provided at one 80 end with means for attaching to it an anchoring-rod, anchoring-rods attached at one end to the ends of said cross-rods, respectively, and extending therefrom in a direction opposite to the direction of rotation of the sweeps, 85 and anchoring-stakes securing the extremities of said anchoring-rods, substantially as shown and described, and for the purpose set forth.

2. In a grinding-mill, an annular base-plate, T, having its upper edge provided with a 90 groove, e, and beveled faces b b on either side of said groove, in combination with a movable ring, S, whose lower edge is provided with a convex central portion conforming to the groove e, and two downwardly-inclined 95 lips, a a', conforming to the beveled surfaces b b, substantially as shown and described, and for the purpose set forth.

3. The combination of the ring S, trunnions V, and lug Q, formed integrally therewith, sweep-levers B, pivoted on said trunnions, cross-bar O, connecting said levers, and recessed, as described, for the reception of said lug, and stirrup P, extending across the bottom of said recess, substantially as shown 100 and described, and for the purpose set forth.

4. The combination of the annular base-plate T, ring S, rotating thereon, integrally-formed converging arms H, provided with lugs M at their outer ends, cone G, suspended 110 from said arms, lugs K on the upper surface of said cone, adapted to engage with the lugs M and insure simultaneous rotation of said ring and cone, and means for rotating said ring, substantially as shown and described, and for 115 the purpose set forth.

SILAS C. SCHOFIELD.
